(57) CLAIM

I claim the ornamental design for spider shaped cupcake holder, as shown and described.

DESCRIPTION

FIG. 1 is a perspective view of my new design;

FIG. 2 is a top view thereof;

FIG. 3 is a bottom view thereof;

FIG. 4 is a right side view thereof, the left side view being a mirror image hereof;

FIG. 5 is a front view thereof; and,

FIG. 6 is a rear view thereof.
